DESIGN FOR A TWIRLING TOY

Edward L. Weinberger, New York, N. Y.

Application January 28, 1946, Serial No. 126,050

Term of patent 14 years

(Cl. D34—15)

To all whom it may concern:

Be it known that I, Edward L. Weinberger, a citizen of the United States of America, and residing at New York city, in the county and State of New York, have invented a new, original, and ornamental Design for a Twirling Toy, of which the following is a specification, reference being had to the accompanying drawing, forming a part thereof.

Fig. 1 is a plan view of a twirling toy, showing my new design.

Fig. 2 is a side view thereof.

The essential features of the design reside in the portions shown in full lines on the drawing. The side not shown is like the side shown on the drawing.

I claim:

The ornamental design for a twirling toy, substantially as shown and described.

EDWARD L. WEINBERGER.
